UNITED STATES PATENT OFFICE.

FEDERICO CAPRONI, OF MILAN, ITALY.

FLYING-MACHINE.

1,325,230.

Specification of Letters Patent. Patented Dec. 16, 1919.

Application filed July 24, 1916. Serial No. 110,880.

To all whom it may concern:

Be it known that I, FEDERICO CAPRONI, a subject of the King of Italy, and resident of 28 Via S. Gregorio, Milan, Italy, have invented certain new and useful Improvements in Flying-Machines, of which the following is a specification.

The object the invention is the construction of a multiplane flying machine of great power and efficiency and capable of maintaining great stability in the air and also permitting of easy landing.

The improvements are connected with the arrangement of the engines, the sustaining planes, the landing carriage frame and details of constructions of such mentioned various parts of the apparatus.

In the annexed drawing is represented by way of example a triplane embodying the improvements that form the object of the present invention.

Figures 1, 2 and 3 represent respectively a front elevation, a plan view and a side elevation of a triplane;

Figs. 4 and 5 represent on a larger scale a side view and a plan view of an essential part of the landing carriage;

Fig. 6 is a detail view of a portion of said carriage on a larger scale.

The triplane comprises two fuselages 1, 2, symmetrically arranged with respect to the center line of the apparatus. Such fuselages are fixed by their fore-ends to the forward body formed by sustaining planes 4, 5, 6. At the rear end of the fuselages 1, 2, are mounted the following planes: A tail plane 7, a horizontal rudder 3, rotatably connected to the horizontal axle 8, three vertical rudders 9, rotatably mounted on axle 10 and joined to one another by means of wires 11, with the view to realizing a simultaneous rotation of same.

The rudder 9 is operated by means of wires 12 which extend to points adjacent the aviator's seat where suitable mechanism is provided for operating the wires. The rudder 3 is operated in a similar way by wires not shown.

The arrangement of the planes 4, 5, 6, is secured by means of two kinds of uprights 13 and 14, arranged in two rows respectively on the front and on the rear of the forward body. The uprights 13 are fixed by their ends 15, 16 respectively to the forward longitudinal frames of the planes 4 and 6 and at-

tached at their center to the plane 5. The uprights 14 are connected at their centers 17 to the rear longitudinal frames of the central plane 5, and by their ends 17' to the longitudinal frames of the planes 4, 6.

On metallic cross-pieces at the points 15 and 17 are joined the stays 18 forming the diagonal members of the chassis of the forward body.

The angles of incidence of the planes 4, 5, 6, and their curvatures are different and established in such a way as to obtain a convenient distribution of the pressure and depressions on said planes.

The angle of incidence of the upper plane 4 is smaller than that of the lower plane 6, and the intermediate plane 5 has an angle of incidence comprised between those of the other two. Moreover, the curvature on the back of surface shall be such as to cause the highest depression, while the curvature underneath the surface 6 shall be such as to cause the highest compression.

The car 19 is mounted through the front body and comprises the aviator-seat, the control devices and rearward the motor 20 driving the propeller 21. Two further motors 22, 23, are arranged on the forward ends of the fuselages 1, 2, which ends project outside the front frame.

The motors 22, 23, are connected directly to the propellers 24, 25.

The landing carriage comprises three sets of wheels 26, 27, 28. The sets 26, 27, are alike and are mounted underneath the front body symmetrically arranged in respect to the central line of the apparatus, and the uprights 14 and fuselages 1, 2. The frames of such sets of wheels are so constructed as to distribute the several strains caused by landing and besides to reduce the resistance of air to progressive movement. The fitting up of wheels on their frames is effected by suitable elastic means in order to have a convenient elastic reaction to the strains caused by landing.

The frames 29 are so made of compound wood that they will be free from distortion and are flat in form. Said flat frame is fixed by its upper end to longitudinal frame 30 of the lower plane 6; it is also curved rearward and prolonged into arm 31 toward the axis of the corresponding fuselage.

The end of arm 31 is connected to frame 32 by means of upright 33. Between the

longitudinal frames 30 and 32 and the center of arm 31 are rigidly arranged the strengthening bars 34, 35.

The axles 36, 37 of the two couples of wheels 38, 39 (Fig 5) are supported at their centers by arm 31 and are tied up by cables or elastic bands, preferably consisting of caoutchouc. The axles 36, 37, are connected to one another by means of metallic rods 42, 10 through a joint, such rods being surrounded by elastic bands 43 that tie them up to arms 31. The fore axle 36 is connected by means of rods 44 to the ends of a rocking member 45, such member being connected by its center through a joint 46 to support 47, fixed on the curved part of frame 29.

Underneath each rod 42 is arranged a stay 48, as well as an extensible upright 49, such arrangement having for its object to 20 conveniently distribute strains on said rod.

The chassis of the landing carriage comprises further a forward pair of wheels 28 their axle 51 being elastically connected to frame 52. Frame 52, formed as a double- 25 armed lever, is connected to a supporting body of which the main upright 54 is elastically connected to the upper end of frame 52 by means of elastic ties 55; 56 is a stay to balance the strain on the elastic 30 tie 55 caused by landing.

The rear skid 57 is joined to frame 58 in the same way as frame 52 to the body 53, 54.

Having now particularly described and ascertained the nature of my said invention 35 and in what manner the same is to be performed, I declare that what I claim is:—

1. A multiplane flying machine comprising in combination two fuselages symmetrically arranged with respect to the center line of the apparatus, two motors arranged on the forward ends of said fuselages, propellers attached to said motors, a tail plane and a horizontal rudder mounted at the rear end of said fuselages, three vertical 40 rudders rotatably mounted at the rear end of said fuselages and means to rotate said vertical rudders simultaneously; a front body consisting of three planes arranged one above the other and wherein the angle of incidence of the upper plane is smaller than that of the lower plane and the middle plane has an angle of incidence comprised between those of the others, two series of uprights 45 for securing the said arrangement of the planes arranged in two rows respectively on the front and on the rear of the said forward

body, the first row of uprights having their ends fixed respectively to the forward longitudinal frames of the upper and lower plane and their center attached to the middle 60 plane, the second row of uprights having one end connected to the rear longitudinal frames of the central plane and having the other ends connected to the longitudinal frames of the upper and lower planes, 65 diagonal members consisting of stay wires, metallic cross pieces for fixing stay wires so that they adjoin the ends of said uprights, a car mounted through the front body and comprising the aviator seat, the control devices, and rearward, a third motor on said car driving a propeller.

2. A landing carriage for a multiplane flying machine comprising in combination a chassis formed of compound wood which 70 is flat in form and constitutes a frame, three sets of wheels to said chassis, two sets being alike, a lower frame curved rearward and formed into an arm, longitudinal members on the chassis, an upright for connecting the 75 said arm to one of said longitudinal members, strengthening bars rigidly arranged between said arm and said longitudinal members of the chassis, axles for the two sets of wheels, bearings for said axles on the 80 center part of the frame arm, metallic rods connecting said axles to one another, elastic bands for connecting together the frame, the axles and the metallic rods, a rocking member on the frame, rods connecting said 85 member to the fore axle, a support fixed on the flat frame and connected at its center through a joint to the said rocking member, a stay member underneath each of said 90 metallic rods, an upright member for 95 stretching said stay, a frame for the third pair of wheels in the form of a double armed lever, means for connecting the axle of the said wheels elastically thereto, a supporting body connected to the said frame, a 100 main upright on the said body, means for elastically connecting the upper end of the said double armed lever to the main upright and a stay to balance the strain on the said elastic connection.

In testimony whereof I have signed my name to this specification in the presence of two subscribing witnesses.

FEDERICO CAPRONI.
